(57) **CLAIM**

The ornamental design for a light-emitting diode and rejuvenating massage device, as shown and described.

DESCRIPTION

FIG. 1 is a front, top, and right side perspective view of a light-emitting diode and rejuvenating massage device according to a first embodiment;

FIG. 2 is a bottom view according the first embodiment;

FIG. 3 is a top view according to the first embodiment;

FIG. 4 is a right side elevational view according the first embodiment;

FIG. 5 is a left side elevational view according the first embodiment;

FIG. 6 is a front elevational view according the first embodiment;

FIG. 7 is a back elevational view according the first embodiment;

FIG. 8 is a front, top, and right side perspective view of the light-emitting diode and rejuvenating massage device with a sleeve according to the first embodiment;

FIG. 9 is a front, top, and right side perspective view of a light-emitting diode and rejuvenating massage device according to a second embodiment;

FIG. 10 is a bottom view according to the second embodiment;

FIG. 11 is a top view thereof;

FIG. 12 is a right side elevational view according to the second embodiment;

FIG. 13 is a left side elevational view according to the second embodiment;

FIG. 14 is a front elevational view according to the second embodiment;

FIG. 15 is a back elevational view according to the second embodiment;

FIG. 16 is a front, top, and right side perspective view of the light-emitting diode and rejuvenating massage device with a sleeve according to the second embodiment;

FIG. 17 is a front, top, and right side perspective view of a light-emitting diode and rejuvenating massage device according to a third embodiment;

FIG. 18 is a bottom view according to the third embodiment;

FIG. 19 is a top view according to the third embodiment;

FIG. 20 is a right side elevational view according to the third embodiment;

FIG. 21 is a left side elevational view according to the third embodiment;

FIG. 22 is a front elevational view according to the third embodiment;

FIG. 23 is a back elevational view according to the third embodiment; and,

FIG. 24 is a front, top, and right side perspective view of the light-emitting diode and rejuvenating massage device with a sleeve according to the third embodiment.

The broken lines in the drawings showing portions of the light-emitting diode and rejuvenating massage device are included for the purpose of illustrating environmental structure and form no part of the claimed design.
